UNITED STATES PATENT OFFICE

COLON J. DUDLEY, OF HAMBURG, NEW YORK, ASSIGNOR TO JOHN S. RICE, OF BIGLERVILLE, PENNSYLVANIA

BASKET-LINING DEVICE

Application filed July 8, 1929. Serial No. 376,536.

My invention relates in general to basket lining devices, and in particular to such devices as are used in connection with baskets to be filled with fruit and the like.

It is well known to those skilled in the art that heretofore liners of this nature have been made in permanent cone-frustum form for fitting into a bushel basket, and of such weight and kind of material that when the basket was placed over a filled liner and inverted, the liner was depended upon to tear at various points so as to increase the size of the liner to permit it and the contained fruit to expand and fill all inequalities in the basket.

The principal object of my invention has been to provide a liner, the ends of which shall be temporarily fastened together, and which ends are released when the liner having been filled with fruit is in place within the basket, whereby the entire liner is permitted to expand within the basket and the contents of the basket thus properly packed.

Moreover, it has been an object to provide a liner which may be used on a variety of sizes and shapes of baskets without breaking, each liner being initially sized before the ends thereof are temporarily secured together.

Furthermore, since one fastening means is used repeatedly, the liners may be inexpensively made; and, since they are made flat, they can be conveniently packed and shipped.

The above objects and advantages have been accomplished by the device shown in the accompanying drawings, of which:

Fig. 1 is a plan view of one of my liners flat and extended.

Fig. 2 is a perspective view of one of my liners rolled up in form and having its ends secured together by the temporary fastening.

Fig. 3 is a side elevation of my liner in position in a bushel basket and filled with fruit.

My invention comprises a liner 5 which is made of suitable sheet material, such as cardboard or heavy paper of the proper strength and stiffness, and of such character that it will readily conform to the shape of the basket or container when the temporary fastening means has been removed. The mate-

rial is, however, stiff and strong enough to support the column of fruit placed within it, while the usual reinforcing shell used in connection with such linings is being removed and the basket being placed over the liner. The side edges 6 and 7 of the liner are arcuate so that when the ends 8 and 9 are brought together a cone-frustum shaped container will be formed. The edges of the ends 8 and 9 are, of course, cut on a line which is radial to the center of the circles of which the arc-shaped edges 6 and 7 are parts. The end 9 is preferably formed with a plurality of radially arranged scored lines 10, which provide means for gauging the size of the complete liner, the edge of the end 8 of the liner being brought into registering position with whichever of the score marks will make the desired size of the cone-frustum of the liner. The liner is preferably provided with a plurality of ventilating holes 11.

When the ends of my liner are brought together so as to provide the proper size, a wire pin or other suitable fastening means 12 is passed a number of times through the lapping ends of the liner as shown in Fig. 2, thus securely fastening them together. This fastening means, as shown in Fig. 2 is provided with a sharpened point 13 at one end and at its opposite end with a ring or eyelet 14. The pin is made of material stiff enough so that it can be easily forced through the material forming the liner.

When the liner is arranged for the packing operation as just above described, it is inverted and placed upon the facing plate usually used in packing operations, whereupon a reinforcing shell is placed around it. This reinforcing shell as well as the facing plate are well known and they are, therefore, not shown in the drawings, since they form no part of my invention. The fruit or other articles being packed are now placed on the inside of the liner and when the same is filled, the reinforcing shell is then removed and the bushel basket 15, shown in Fig. 3, or other crate or container being used, is placed over the liner, and the basket, liner, facing plate, and the contents of the liner are inverted, whereupon the facing plate is re-

moved. The pin 12 is now withdrawn from the ends of the liner which releases the ends of the liner and permits it to freely expand, as shown in Fig. 3, to a degree necessary to 5 permit the liner with its contents to settle in the basket and to conform to the inner surface of the basket when shaken or jolted. The temporary fastening pin 12, after having been removed from the liner, is immediately 10 ready for reuse.

Obviously, some modifications of the details herein shown and described may be made without departing from the spirit of my invention or the scope of the appended claims, 15 and I do not, therefore, wish to be limited to the exact embodiment herein shown and described, the form shown being merely a preferred embodiment thereof.

Having thus described my invention, what 20 I claim is:

1. As a new article of manufacture, a packing liner for use in packing fruit and the like having removable means coacting with portions of the liner to hold the same against 25 expansion, the liner, when said means is removed, being so constructed as to permit expansion of the liner, said means permitting its removal to be effected when the liner is full without the disturbance of the content 30 therein.

2. As a new article of manufacture, a packing liner for use in packing fruit and the like having removable rod coacting with portions of the liner to hold the same against 35 expansion, the liner, when said rod is removed, being so constructed as to provide expansion of the liner, said rod permitting its removal to be effected when the liner is full without disturbance of the content there- 40 in.

40 In testimony whereof, I have hereunto signed my name.

COLON J. DUDLEY.
